DESIGN FOR A GLASS PINEAPPLE DISH OR ARTICLE OF SIMILAR NATURE

Belle Kogan, New York, N. Y., assignor to The Federal Glass Company, Columbus, Ohio, a corporation of Ohio

Application August 30, 1940, Serial No. 94,732

Term of patent 3½ years

To all whom it may concern:

Be it known that I, Belle Kogan, a citizen of the United States of America, residing at New York, in the county of New York and State of New York, have invented a new, original, and ornamental Design for a Glass Pineapple Dish or Article of Similar Nature, of which the following is the specification, reference being had to the accompanying drawing, forming a part thereof.

apple dish or article of similar nature, showing my new design.

I claim:

The ornamental design for a glass pineapple dish or article of similar nature, substantially as shown.

BELLE KOGAN.
